UNITED STATES PATENT OFFICE.

TILLMANN P. FLIEGENSCHMIDT AND LOUIS V. PRINZLER, OF INDIANAPOLIS, INDIANA.

COOLING-COIL PROTECTOR.

1,190,746.

Specification of Letters Patent. Patented July 11, 1916.

Application filed September 30, 1915. Serial No. 53,335.

To all whom it may concern:

Be it known that we, TILLMANN P. FLIEGENSCHMIDT and LOUIS V. PRINZLER, citizens of the United States, residing at Indianapolis, in the county of Marion and State of Indiana, have invented certain new and useful Improvements in Cooling-Coil Protectors, of which the following is a specification.

10 This invention relates to coils used in boxes for cooling beer, water and other liquids for drinking purposes, wherein the temperature of the liquid which is drawn through a pipe arranged in a coil in the box, 15 is cooled by surrounding the coil with broken ice.

Damage is done to the coil which is generally of lead, by the mashing together of the walls, particularly of the top convolution, 20 due to haste and carelessness in depositing and packing the ice in the box. Often, also, the box is filled too full and the ice is compressed and hammered down to get the lid closed, and the flattening together of the 25 walls of the coil retards the flow through it and frequently cuts it off altogether.

The object of this invention is to provide a guard or shield for the upper end of the coil which receives the impact in icing the 30 box.

We accomplish the object of the invention by the device illustrated in the accompanying drawing, in which—

Figure 1, is a vertical cross section of an 35 ice-box containing a spiral coil provided with our improved guard. Fig. 2 is a top plan view of the coil and guard on a much larger scale than is shown in Fig. 1. Fig. 3 is a side elevation of the upper end of the 40 coil with guard attached as in Fig. 2, and Fig. 4 is a section on the line 4—4 of Fig. 2.

Like characters of reference indicate like parts throughout the several views of the drawing.

45 Referring to Fig. 1, 5 is the ice-box of any suitable size, shape and construction within which is located a coil 6, of spirally wound pipe—usually lead pipe—through which a liquid to be cooled passes from the 50 lower member 7 and is drawn off through an upper member 8 and faucet 9. A stand-pipe 10 keeps the water from the melted ice-pack above the highest coil. Broken ice is intro-

duced into the box through its top which is opened by removing the lid 11. 55

The guard 12 is a cast annulus, preferably of brass on account of the hard and non-corrosive qualities of that metal. It is formed with an underside channel of such a depth as will receive all of the top convolution and approximately half of the second one of the series of convolutions in the complete coil. The walls of the channel will be of greatest thickness on top where the greatest impacts and coil-flattening pressures will 60 be delivered, and the outer surface will preferably taper upwardly to a central line forming a ridge which will tend to separate the broken ice when the latter is pressed against it and thereby reduce the force of 65 the blows which flatten the coil when the ice is pounded down to get the lid on the box.

The shape of the guard and channel conforms to that of the spiral convolutions of the lead coil so the guard will lie firmly 75 against the top one, and to keep the guard from being pounded loose we solder its lower edge at 13 to the second convolution as shown in Fig. 4.

While we have described our invention 80 with more or less minuteness as regards details of construction and arrangement, we do not desire to be limited thereto unduly or any more than is pointed out in the claims. On the contrary, we contemplate 85 all proper changes in form, construction and arrangement as circumstances may suggest or necessity render expedient.

We claim—

1. In an ice-box having a pipe formed in 90 a spiral coil through which a liquid is passed to be cooled, a guard supported entirely by the coil, said guard being in the form of an annulus having an underside channel which receives the top convolution with a close fit 95 against its top by conforming to the spiral shape of said convolution, and receives part of the next lower convolution and is soldered to the latter.

2. In an ice-box having a pipe formed in 100 a spiral coil through which a liquid is passed to be cooled, a guard supported entirely by the coil, said guard being in the form of an annulus having an underside channel which receives the top convolution with a close fit 105 against its top, and receives part of the one

below and is soldered to the latter, the channel being shaped to fit close against the top of the top convolution, the outer walls of the guard tapering upwardly to a central line extending longitudinally of the annulus.

In witness whereof, we have hereunto set our hands and seals at Indianapolis, In-

diana, this 14th day of September, A. D. one thousand nine hundred and fifteen.

TILLMANN P. FLIEGENSCHMIDT. [L. S.]
LOUIS V. PRINZLER. [L. S.]
